UNITED STATES PATENT OFFICE.

JOHN O. NEIKIRK, OF LOMBARD, ILLINOIS, ASSIGNOR TO NATIONAL DUMP CAR COMPANY, OF CHICAGO, ILLINOIS, A CORPORATION OF MAINE.

CAR.

Application filed April 3, 1924. Serial No. 703,904.

The present invention relates to cars, and more particularly to a structural member having increased strength which may be so placed in the car as to increase the carrying capacity of the car and greatly facilitate the discharge of dumpable material when used in connection with dumping cars.

Referring to the drawings—
10 Figure 1 is a view in side elevation of an end portion of a car embodying the principles of the present invention;

Figure 2 is a top plan view of the construction illustrated in Figure 1;
15 Figure 3 is a sectional view taken along a plane indicated by the arrows 3—3 of Figure 2;

Figure 4 is a fragmentary view, on an enlarged scale, of the structure shown in
20 Figure 2;

Figure 5 is a fragmentary view showing a view in side elevation on an enlarged scale, said view corresponding to Figure 1;

Figure 6 is a view in end elevation of the
25 structure shown in Figures 4 and 5;

Figure 7 illustrates a detail of construction;

Figure 8 is a sectional view of a stake such as is commonly provided in railway
30 cars as at present known and used; and

Figures 9 and 10 illustrate in section two forms of stake which provide decided improvements over the structure of Figure 8.

In the present embodiment of my invention
35 I have illustrated a dumping car, although it will be understood that the new structural member is adapted for use in other types of cars as well.

The numeral 10 indicates one of the side walls of a railway car embodying the principles of the present invention. In the illustrated embodiment the walls 10—10 are vertical. The numeral 11 indicates a sloping end wall which slopes from a region adjacent to the end of the car at the top of said car to a region adjacent to certain dumping mechanism indicated by the numeral 12. It will be understood that the two ends of the car may be substantially alike, so that a description of one end will suffice for a description of both ends of the car. The side walls 10—10 may be united to the sloping end wall 11 by means of sloping walls 13—13, said vertical walls
50 10—10 and sloping walls 11 and 13—13

forming shedding walls whereby lading will be directed toward the dumping mechanism 12.

The numerals 14—14 indicate vertical stakes, which may be riveted to the side walls 10—10. The numerals 15—15 indicate top chords which extend longitudinally of the car and are riveted or otherwise secured to the vertical side walls 10—10. In railway cars as commonly known and used, the stakes and chords have been provided exteriorly of the side walls, whereby the overall dimensions transversely of the car were defined not by the side walls but by said stakes and chords.

According to the present invention, the stakes 14—14 and chords 15—15 are disposed interiorly of the walls 10—10. By reason of this construction, the walls 10—10 may be disposed at such a distance apart that the distance between the outer side of said walls is substantially the maximum dimension permitted by the railway regulations for the overall transverse dimension of the car.

By reason of this construction, the amount of lading which may be carried is materially increased over cars as now commonly used.

The numeral 16 indicates a heap of lading carried by the car, which heap, it will be noted, is bounded at the sides of the car by
55

planes spaced apart a distance equal to substantially the overall width of said car. It will be noted that the chords 15 and the stakes 14 are angular in cross section, the end of the legs being pressed outwardly to form flanges 17 lying in the same plane. I form this member by pressing an angular rolled section into the form desired. This results in a section which has a fillet at the angle thus forming a member which has its greatest strength at the desired point. It will be noted that in using this member as a top chord, I place it with the flanges 17 in a vertical plane, these flanges being riveted to the car sides, the convex surface of the angle being inwardly disposed so as to form the upper surface of said chord, both the upper and lower surfaces of the angle extending to the car side. It will be thus seen that in loading the car, the load in the body of the car is contained in the maximum width of the car up to the lower surface of the chord and is heaped above the body of the car to the full width of the car and resting on the upper surface of the chord. reason of the inclination of this upper surface the load supported thereon is readily discharged from a dumping car. It will be further seen that by reason of the section 5 as applied to the inside stakes, the legs of the angle converge in the direction of the discharge of the load so that there is no tendency for the load to be retarded in its discharge from a dumping car. These particular advantages of facility in unloading 10 are, of course, additional to the strengthening of these members when used in any type of car. In ordinary practice the stake is formed as shown in Figure 8, by pressing a 15 plate into the form here shown. This operation results in a thinning of the material at the angle thus weakening the member at that point.

As indicated in Figures 1 and 3, the stakes 20 14—14 are extended upwardly a sufficient distance to overlie the adjacent flange 17 of the corresponding top chord 15, said stakes 14, top chord 15 and the corresponding wall 10 being riveted together to form a rigid 25 structure.

In order to provide a connecting means 30 between the top chords 15—15 and the ends of the car, the present invention contemplates certain connecting means illustrated 35 in Figure 7. Said connecting means, which is indicated by the numeral 18, is provided with an angular portion 19 adapted to overlie the chord 15 upon which it is mounted. Integrally connected to the portion 19 is 40 the angular portion 20, which, as will be explained hereinafter, should be of sufficient size interiorly thereof to permit a hand hold on a bar disposed substantially within the outlines of said angular portion 20. Integrally united to the portion 20 is the plate 45 21, which may be riveted to the end portion of the car. It will be understood that the portion 19 and portion 20 of the member 18 may be riveted to the corresponding side wall 10 whereby to provide a rigid structure which will effectually shed lading interiorly of the car.

By reason of the structure illustrated and 50 described, a hand rail 22 may be provided at the top of the car disposed in a position such that said hand rail, though occupying a minimum of space transversely of the car, may be readily grasped by an operator. The side wall 10 adjacent thereto is cut away 55 to permit access to the concave side of the angular portion 20. Said hand rail 22 is bent at the region 23 intermediate of its length and has its two ends riveted to the car body near the top thereof, as indicated 60 by the numerals 24—24. It will be noted from an inspection of Figure 5 that that portion of the hand rail 22 which extends along the side of the car is disposed in a position symmetrical with the angular portion 65 20 of the connecting member 18. By

reason of this construction the hand rail 22 may be readily grasped by an operator, even though said hand rail extends only slightly beyond the plane of the outer side of the adjacent wall 10.

Attention is directed to the improved form of stake provided by the present invention. It has been common practice heretofore to provide stakes and top chords by pressing same from a strip of flat steel. A common form of stake is illustrated in Figure 8. Said stake, which is indicated by the numeral 25, is provided with the side flanges 26—26, the walls 27—27 and the rounded crest portion 28. Due to the method of manufacturing such a stake, the metal at the crest 28 is frequently so distorted that the stake is materially weakened. According to the present invention, the weakening immediately above referred to is obviated. Referring to Figure 9, an angle, indicated by the numeral 29, is provided. Said angle is swedged at the edges thereof to provide the flanges 17—17. By reason of this method of manufacture, no weakening of the stake is involved. According to the structure illustrated in Figure 10 a structural shape is provided having the flanges 17—17, the side walls 27—27, and a reinforced crest which is indicated by the numeral 28'. By reason of said reinforced crest, a stake is provided having all the rigidity required in practice.

Though a preferred embodiment of the present invention has been illustrated and described, it will be understood that many modifications will occur to those skilled in the art. It is intended to cover all such modifications that fall within the scope of the appended claims.

What is claimed is:

1. A railway car for carrying lading, comprising a side wall, a top chord arranged adjacent to the top of said wall, said top chord comprising an angular member arranged along the top of said wall with the apex of said angular member facing interiorly of said car, an end portion for said car, a member for joining said top chord to said end portion, said member having an angular portion conforming to said top chord and having an angular portion the concave side of which faces outwardly of said car, and a hand rail located adjacent to said outwardly facing angular portion whereby said hand rail may be conveniently grasped by an operator, said member being united to said end portion.

2. A railway car for carrying lading, comprising a side wall, an end portion, a top chord, a member joined to said end portion for forming a smooth joint with said top chord, said top chord comprising an angular member mounted interiorly of said car, said member having an angular portion

conforming to said top chord and having an angular portion the concave side of which faces outwardly of said car, and a hand rail mounted adjacent to said outwardly facing angular portion whereby said hand rail may be conveniently grasped.

3. A railway car for carrying lading, comprising a side wall, a stake and a top chord mounted upon said side wall interiorly of said car, said stake and chord comprising angular members, said angular members

having their inwardly presented extremities of a strength greater than the strength of the other portions of said angular members.

4. A railway car having a top chord of 15 angular cross section, said top chord having its concave side outwardly disposed and a ladder round opposite the concave side of said angular top chord.

Signed at Chicago, Illinois, this 31st day 20 of March, 1924.

JOHN O. NEIKIRK.
